VEHICLE JACK

Anton Goeller, Iberia, Mo.

Application December 30, 1948, Serial No. 68,255

5 Claims. (Cl. 254—7)

1

The present invention relates to new and useful improvements in jacks and more particularly to a vehicle jack for use with trucks or other motor vehicles.

An important object of the invention is to provide a heavy duty jack of this character embodying a screw-operated means whereby the jack may be raised with comparatively little effort.

A further object of the invention is to provide a jack including a load supporting platform raised and lowered by lift arms arranged in crossed relation with respect to each other and connected at their lower ends to a telescoping or extensible frame operated by the screw in a retracting movement to raise the platform.

A further object of the invention is to provide a collapsible inverted V-shaped brace for the lift arm and which is moved into its raised and lowered positions with the lift arms by the telescoping movement of the frame.

A still further object is to provide a device of this character of simple and practical construction, which is strong and durable, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view showing the jack in its lowered position;

Figure 2 is a similar view showing the jack raised;

Figure 3 is a front elevational view;

Figure 4 is a top plan view;

Figure 5 is an enlarged fragmentary sectional view taken on a line 5—5 of Figure 4;

Figure 6 is an enlarged fragmentary sectional view of the ratcheting means for operating the screw and taken on a line 6—6 of Figure 4;

Figure 7 is a horizontal sectional view taken on a line 7—7 of Figure 2 and showing the telescoping or extensible frame; and

Figure 8 is a horizontal sectional view taken on a line 8—8 of Figure 2.

Referring now to the drawings in detail, where-
in for the purpose of illustration I have disclosed a preferred embodiment of the invention, the nu-
meral 5 designates the jack frame generally and
which comprises front and rear U-shaped tele-
scoping frame members 6 and 7, the frame mem-
ber 7 being of tubular construction to telescopi-

2

cally receive the sides of the frame member 6 in a sliding movement into its extended and retracted positions.

A screw 8 has its rear end welded or otherwise suitably secured to the central portion of the rear frame member 7, and extends forwardly in the plane thereof and is slidably received in a sleeve 9 carried at the central portion of front frame member 6. A nut 10 is threaded on the front end of screw 8 in engagement with the front end of sleeve 9 and the front end of nut 10 is formed with a ratchet wheel 11 including the ratchet teeth 12. A handle 13 is provided at its inner end with a U-shaped yoke 14 having its open end pivoted on nut 10 with parallel side portions 15 positioned at opposite sides of the teeth 12 as shown more clearly in Figure 5 of the drawings to hold the yoke on the nut during its pivotal movement.

20 A reversible dog 16 is pivoted between the side portions of yoke 14 by means of a transverse pin 17 and is held in oppositely swung positions engaged with the teeth 12 by means of a spring 18. A reversing lever 19 projects from the dog 16 at one side of yoke 14. The handle 13 is positioned on the screw 8 to project outwardly at one side of frame 5 as shown in Figure 4 of the drawings.

The rear corners of rear frame section 7 are 30 supported on swivel or caster rollers 21 and the front corners of front frame section 6 are similarly supported on rollers 21' to facilitate movement of front frame section 6 forwardly and rearwardly upon the operation of handle 13 to feed nut 10 and force sleeve 9 in a raising movement. A collapsible inverted V-shaped brace 21 is 35 constructed of front and rear sections 22 and 23 pivotally connected to each other at their upper ends by a conventional type of hinge structure 24. The lower end of rear brace member 23 is pivoted to the rear portion of rear frame member 7 by a conventional type of hinge structure 25 and the lower end of front brace member 22 is similarly pivoted to the front end of front frame member 6 by conventional hinge structure 26. A pair of tubular sockets 27 are suitably secured to the upper surface of rear brace member 23 and in which the lower ends of a rear inverted U-shaped lift arm 28 are received and 40 secured in vertically adjusted position by pins or set screws 29 selectively received in a row of openings 30 carried by each socket.

The upper end of U-shaped arm 28 is slidably received in a guide 31 secured to the underside 45 and at the front portion of a platform 32.

A front inverted U-shaped lift arm 33 is simi-

larly supported on front brace member 22 with its lower ends adjustably engaged in sockets 34 suitably secured to the upper surface and at the lower portion of the front brace member. The upper end of lift arm 33 is rockably secured to the underside of platform 32 at its rear portion by bearing brackets 35.

The upper portion of lift arms 28 and 33 above the brace 21 are crossed as shown in Figure 2 of the drawings and in the operation of the device the jack is held in its lowered position by operating handle 13 and swinging pivoted dog 16 in a direction to feed nut 10 forwardly on screw 8 whereby the weight of the jack will slide sleeve 9 forwardly on screw 8 and slide front frame member 6 forwardly. When in their lowered positions the brace members 22 and 23 rest on a cross bar 36 suitably secured in a transverse position on the front ends of rear frame member 7, to hold the brace and lift arms 28 and 33 in a slightly upwardly inclined position as shown in Figure 1 of the drawings.

To raise the jack the dog 16 is swung into a position for operating ratchet 11 in a direction to feed nut 10 in a rearward direction on screw 8 thereby forcing sleeve 9 rearwardly which also moves front frame member 6 rearwardly in rear frame member 7 and causes a raising movement of brace members 22 and 23 together with the lift arms 28 and 33 carried thereby.

The front corner of front frame member 6, adjacent handle 13 is provided with a handle 37 projecting laterally from the frame and parallel to the handle 13 to provide a convenient grip for one hand of a person while the other hand is used in operating the handle 13. The handle 37 is also used to guide the frame 5 into its position under a vehicle.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A jack comprising a horizontally extensible base, screw operating means for moving the base into and out of its extended position, a collapsible brace carried by the base, a pair of inclined crossed lift arms carried by the brace, and a plat-

form at the upper ends of the lift arms, said brace comprising a pair of sections hinged together and to said base for upward swinging in angular relation when said base is moved out of extended position, said crossed lift arms being mounted on said sections for upward swinging thereby.

2. A jack comprising a horizontally extensible base, screw operating means for moving the base into and out of its extended position, a collapsible inverted V-shaped brace carried by the base, a lift arm supported by each side of the brace and extending upwardly therefrom, said lift arms being crossed with each other, and a platform at the upper ends of said lift arms.

3. A jack comprising a horizontally extensible base, screw operating means for moving the base into and out of its extended position, a collapsible inverted V-shaped brace carried by the base, a pair of lift arms carried by and lying against the outer surfaces of the brace with the upper ends of the lift arms crossed, and a platform at the upper ends of the lift arms.

4. A jack comprising a horizontally extensible base, screw operating means for moving the base into and out of its extended position, a collapsible inverted V-shaped brace carried by the base, a lift arm lying against the outer surface of each side of the brace with the upper ends of the arms crossed with each other, means securing the lift arms in vertically adjusted position to the brace, and a platform at the upper ends of the lift arms.

5. A jack comprising a frame composed of horizontally extensible frame members, a jack screw fixed horizontally to one frame member and with respect to which the other frame member is slidable, ratcheting means engaging the screw to actuate the last-named frame member, a collapsible V-shaped brace having its ends pivoted to the respective frame members and rising therefrom, lift arms secured against the outer sides of the brace and crossed above the brace, and a platform at the upper ends of the lift arms.

45 ANTON GOELLER.
